UNITED STATES PATENT OFFICE.

ROBERT O. DOHM, OF DANE, WISCONSIN.

DRAIN-VALVE.

1,239,574.

Specification of Letters Patent. Patented Sept. 11, 1917.

Application filed January 12, 1917. Serial No. 142,031.

To all whom it may concern:

Be it known that I, ROBERT O. DOHM, a citizen of the United States, residing at Dane, in the county of Dane and State of Wisconsin, have invented certain new and useful Improvements in Drain-Valves, of which the following is a specification.

This invention relates to improvements in pumps, and has for one of its objects to pro-

10 vide a simply constructed attachment whereby means are provided for discharging the water in the upper portion of a pipe stock to cause the removal of all the water above the freezing point.

15 Another object of the invention is to provide a simply constructed device which may be operated from the ground above and without disturbing the curbing or the other stationary parts of the pump.

20 Another object of the invention is to provide a simply constructed device which may be readily applied without material structural changes to pumps of various forms and constructions.

25 With these and other objects in view the invention consists in certain novel features of construction as hereafter shown and described and then specifically pointed out in the claims, and in the drawings illustrative 30 of the preferred embodiment of the invention.

Figure 1 is a side elevation of portions of a conventional pump with the improvement applied.

35 Fig. 2 is an enlarged elevation of the improved attachment.

Fig. 3 is a section on the line 3—3 of Fig. 2.

40 Fig. 4 is a section on the line 4—4 of Fig. 2.

Corresponding and like parts are referred to in the following description and indicated in all the views of the accompanying drawings by the same reference characters.

45 The improved device may be applied to any portion of a pump below the frost line, but is preferably attached to the main outlet pipe 10 relatively near the barrel or cylinder 11 as shown. The improved device 50 comprises a base portion 12 slightly concave at one side and with a central protuberance 13. The pipe 10 is provided with a vent aperture 14 with the outer portion of the vent counter-sunk to receive the protuberance 13. The counter-sunk portion of 55 the vent and the protuberance 13 closely cor-

respond in outline and are so constructed that when the member 12 is clamped against the pipe with the protuberance engaging in the counter-sunk portion of the vent, a 60 water-tight joint will be provided between the parts. The member 12 is clamped in any suitable manner to the pipe 10, preferably by a U-bolt 15 and clamp nuts 16.

Extending from the rear face of the base 65 member 12 is a bracket-like structure 17 having an intermediate transverse recess 18 with the portion of the bracket between its recess and its upper end provided with a threaded aperture to receive a shut-off screw 70 19. Extending through the base member 12 and likewise through the protuberance 13 and into the lower portion of the bracket 17 is an orifice or vent 20, and directed upwardly from the inner end of the vent 20 75 is a branch vent 21 which opens into the lower end of the opening 18 of the bracket. The upper end of the branch vent 21 is counter-sunk while the lower end of the screw 19 is convex to engage in the counter- 80 sunk portion of the branch vent so that when the screw is turned downwardly, the vent 21 will be shut off and rendered water-tight.

At its upper end the screw 19 is provided with an eye 22 to receive a hook on a turning 85 rod 23. The rod extends upwardly through the floor of the curb of the well in convenient position to be manually actuated.

By this simple means, it will be obvious that when it is desired to draw off the water 90 from the pipe 10, as for instance when danger of freezing arises, it is only necessary to rotate the rod 23 reversely a few turns to cause the convex point of the screw 19 to be withdrawn from engagement with the counter-sunk terminal of the vent 21 and thus permit the water to escape from the pipe. When the pump is to be again used, it is only necessary to reverse the movement of the rod 23 to close the vent and permit the water 100 to rise into the pipe.

The recess 18 opens away from the adjacent wall of the well so that the escaping jet of water will not be thrown against the wall, but will be deflected toward the pipe 10 105 and thus caused to flow downwardly over the cylinder.

The improved device is simple in construction, can be inexpensively manufactured and applied without changes to the 110 pipe except to drill the vent 14 in the pipe and countersinking the outer terminal.

A stop pin 25 extends through the screw 19 within the recess 18 to limit the upward movement of the screw, and prevent its detachment from the bracket.

5 Having thus described the invention, what is claimed as new is—

1. In a device of the class described, a body having right-angled passages with a seat externally of one of the passages and a 10 seat internally of the other passage, said body adapted to be secured to a conduit with the external seat adapted to engage an opening in the conduit, a projection on said body and having a laterally opening recess communicating directly with the passage having the internal seat and rendering the seat

accessible, and a valve device operating through the projection and engageable with the internal seat.

2. In a device of the class described, a 20 body having passages with seats at their ends, said body adapted to be secured to a conduit with one of said seats adapted to engage an opening in the conduit, a projection on said body and having a laterally 25 opening recess communicating with the other seat and rendering the same accessible, and a valve device operating through a projection and engageable with the last-mentioned seat.

In testimony whereof I affix my signature. 30

ROBERT O. DOHM. [L.S.]
